UNITED STATES PATENT OFFICE.

GEORGE H. PHELPS, OF NEWTON, MASSACHUSETTS, ASSIGNOR TO THE
GEORGE FROST COMPANY, OF BOSTON, MASSACHUSETTS.

DESIGN FOR A STUD.

SPECIFICATION forming part of Design No. 27,809, dated November 2, 1897.

Application filed February 18, 1897. Serial No. 624,048. Term of patent 14 years.

To all whom it may concern:

Be it known that I, GEORGE H. PHELPS, a citizen of the United States, residing at Newton, in the county of Middlesex and State of Massachusetts, have invented and produced a new and original Design for Studs or Buttons for Garment-Supporters, of which the following is a specification.

The object of my invention is to produce a design for a stud or button, such as is commonly used in connection with a loop in garment-supporters, of an improved ornamental appearance.

My design consists of a stud or button having a cylindrical shank and an enlarged head, the central portion of which is sunken, shallow, conical, and lustrous, and which is surrounded by an outer portion having a relatively dull or deadened appearance, and which joins the outwardly-sloping sides of the conical central portion, has a circular periphery, and extends on its under side toward the shank.

In the accompanying drawings, Figure 1 is a front elevation of a stud or button containing my design mounted on a plate or base. Fig. 2 shows a perspective view thereof.

B indicates the central shallow sunken portion, and A indicates the annular surrounding portion. The depression b is somewhat conical. The drawings show a flat ring b' left at the edge of the central portion B, where it joins the annular portion A.

The essential feature of my design is a stud or button having a cylindrical shank and an enlarged head, the central portion of which is sunken, shallow, conical, and lustrous, and which is surrounded by an outer portion having a relatively dull or deadened appearance and which joins the outwardly-sloping sides of the conical central portion, has a circular periphery, and extends on its under side toward the shank.

I claim—

The design for a stud or button for garment-supporters, substantially as herein shown and described.

GEORGE H. PHELPS.
